US00D524596S

(12) **United States Design Patent** (10) Patent No.: **US D524,596 S**
(45) Date of Patent: **** Jul. 11, 2006**

(54) **THERMOSIGNAL HANDLE FOR COOKING UTENSIL**

(75) Inventor: **Guy Magnouloux**, Annecy (FR)

(73) Assignee: **Tefal**, Rumilly (FR)

(**) Term: **14 Years**

(21) Appl. No.: **29/219,270**

(22) Filed: **Dec. 14, 2004**

(30) **Foreign Application Priority Data**

Jun. 21, 2004 (FR) 04 3072

(51) **LOC (8) Cl.** **07-02**

(52) **U.S. Cl.** **D7/393**

(58) **Field of Classification Search** D7/350.3,
